[57] CLAIM

The ornamental design for a seating module, as shown and described.

DESCRIPTION

FIG. 1 is a front perspective view of a seating module showing our new design;

FIG. 2 is a top plan view thereof;

FIG. 3 is a bottom plan view thereof; and,

FIG. 4 is a front elevational view, the rear and sides being identical thereof.

FIGS. 2, 3, and 4 have been drawn on an enlarged scale with respect to FIG. 1.

FIG. 1

FIG. 2

FIG. 3

FIG. 4
